UNITED STATES PATENT OFFICE

FRED A. MOSHER, OF GRAND RAPIDS, MICHIGAN, ASSIGNOR TO LOGAN-LONG COMPANY, OF CHICAGO, ILLINOIS, A CORPORATION OF OHIO

SHINGLE AND METHOD OF MAKING SAME

Application filed April 24, 1929. Serial No. 357,726.

This invention relates to improvements in shingles and method of producing same and it consists of the matters hereinafter described and more particularly pointed out in the appended claims. It relates more particularly to so called composition shingles.

Composition shingles, manufactured by cutting strips of shingle material into shingles of predetermined size, present such regularity when laid, as to lack character. Hence they often detract from the appearance of the dwelling upon which they are used because such regularity does not harmonize with the architecture of said dwelling.

15 One of the greatest obstacles to the larger use of composition shingles has been the lack of that artistic touch or element often referred to as character or beauty.

The general object of my invention is to 20 provide a composition shingle and a method of producing same which shall present an artistic appearance when laid.

It is also an object of my invention to provide such a shingle and a method of producing 25 same which shall not destroy the utilitarian characteristics of the shingle.

Again I aim to provide a method of producing such improved shingles, which method shall be simple, easily understood and practiced and which shall add little to the cost 30 of the shingle while greatly improving its appearance.

The foregoing and other objects are accomplished by providing a shingle having an 35 artistic and pleasing appearance, whether it be rectangular, hexagonal or other shape, which shingle has its exposed bottom edge formed in an irregular and wavy shape, so that when laid upon a roof, the weather or 40 butt edge of the shingles present an irregularity which avoids the severe straight line effect usually presented by composition shingles.

The objects of the invention are also accomplished by providing a shingle having an 45 irregular bottom edge of no particular pattern and one which is charred to slightly swell the same, thereby increasing high-light effects and diminishing the regularity of appearance 50 so that the shingles will more readily fit in

with the appearance of a dwelling regardless of its architectural lines or characteristics.

To accomplish the foregoing objects of the invention I also provide a simple and efficient method for so treating shingles and especially 55 when arranged in bundle form as to impart a novel contour and appearance to the weather or butt edges thereof.

These objects of the invention as well as others, together with the many advantages 60 thereof, will more fully appear as I proceed with my specification.

In the drawings:—

Fig. 1 is a view in elevation of a plurality of shingles embodying my invention as when 65 laid in order upon a roof.

Fig. 2 is a perspective view of a bundle of shingles being operated upon in accordance with one of the steps of my improved method.

Fig. 3 is a similar view to Fig. 2, illustrating the shingles as being operated upon in accordance with another one of the steps of my improved method.

Fig. 4 is a detail sectional perspective view 75 through the weather or butt end of a shingle made in accordance with my invention.

The shingles with which my invention is concerned and which are known as "composition" shingles, include shingles having a 80 fibrous and asphaltic base or body with or without the usual protective covering or coating of granular substances employed in shingles of this kind.

In carrying out the improved method, the 85 shingles may be operated upon either individually or collectively with the same results but as operating upon individual shingles is slow, laborious and costly and as operating simultaneously upon a plurality of shingles is simpler and more economical, I 90 will describe the method as when operating simultaneously upon a plurality of shingles.

Shingles of this kind usually come in 95 bundles or bunches and are normally bound together in that relation. In Fig. 2 is illustrated a bundle of shingles 1—1 bound together in bundle form by metallic bands or wires 2—2. I take such a bundle of shingles 100

and stand them on a suitable support with those edges which are to form the weather or butt edges thereof, uppermost.

Thereafter I take an implement or tool such as a hatchet or axe 3 and chop or hack said uppermost end of the bundle, promiscuously to mutilate the same. In this chopping or hacking no regularity is sought and some of the cuts made will cross each other and in some instances chunks will be cut out of said edges to leave notches 4—4 in said edges. Thereafter I remove the loose particles and débris from said bundle end in any suitable manner as by brushing or sweeping the same and the bundle end will then appear as having notches of V-shape and otherwise together with cuts and slashes, distributed indeed irregularly over the entire area of said bundle end as in Fig. 3.

I next char the bundle end in any suitable manner as by playing the flame from a torch 5 thereover and this rounds off all the sharp corners of the cuts and recesses. In shingles having granular protective coatings 7 impressed into the more heavily asphalted surface thereof, I find that such a surface burns or chars farther back than does the fibrous body so that the more heavily asphalted surface slightly swells and thus forms a thicker ridge 8 along said edge. Again a slight discoloration of the granular protective particles adjacent said edge takes place but this discoloration merges so gradually into the undcolored part that it assists in further reducing the regularity of appearance to better attain the irregularity desired. In this charring or burning of the ends of the shingles, the same may be carried down the side edges of the shingles for a short distance, enough to reduce the regular or straight edges formed by cutting the strips into shingles.

When the shingles are laid upon a roof as in Fig. 1, the exposed edges of one course are not so severely straight and regular but have undulatory edges which include irregularly shaped and spaced recesses 9 without harsh square corners. Thus the shingles may be employed upon any type of dwelling and are universal so far as laying them for any desired effect is concerned. When laid the charred edges produce better high-light effects so that the laid roof will have a distinguished and pleasing appearance and character and will not be severe in its regularity.

While in describing my invention, I have referred in detail to the form, arrangement and construction of the various parts thereof, as well as to the steps by which the shingles are produced, the same is to be considered merely as illustrative so that I do not wish to be limited thereto except as may be pointed out in the appended claims. For example the irregular or wavy edge may be provided at the time the shingle is cut instead of after it has been formed. The se-

quence of other of the steps may also be modified.

I claim as my invention:

1. The steps in the manufacture of composition shingles having at least one edge thereof in regular outline, which steps consist in mutilating said edge and then charring the same. 70

2. The steps in the manufacture of composition shingles, which steps consist in providing a plurality of shingles in grouped face to face relation, which shingles each has at least one edge of regular outline, and simultaneously mutilating said edges and then charring the same. 75

3. The steps in the manufacture of composition shingles which consist in providing a plurality of shingles in grouped face to face relation, which shingles each has at least one edge of regular outline, mutilating said edges, removing the débris and particles formed by so mutilating said edges and then charring said edges. 85

4. The step in the manufacture of composition shingles which consists in swelling one edge thereof by charring the same. 90

5. The steps in the manufacture of composition shingles which consist in mutilating one edge thereof and swelling said edge by charring the same. 95

6. A composition shingle having a mutilated and charred edge.

In testimony whereof, I have hereunto set my hand, this 20th day of April, 1929.

FRED A. MOSHER.
